US0D1019449S

(12) **United States Design Patent** (10) Patent No.: **US D1,019,449 S**
(45) Date of Patent: ** Mar. 26, 2024

(54) **BAND**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/736,040**

(22) Filed: **May 27, 2020**

Related U.S. Application Data

(63) Continuation of application No. 29/677,348, filed on Jan. 18, 2019, now Pat. No. Des. 885,959, which is a continuation of application No. 29/596,819, filed on Mar. 10, 2017, now Pat. No. Des. 838,619.

CLAIM

The ornamental design for a band, as shown and described.

DESCRIPTION

FIG. 1 is a front view thereof;

FIG. 2 is a front left side view thereof; and,

FIG. 3 is a top front perspective view thereof.

The dot-dash lines in the figures and the areas within the dot-dash lines show portions of the band that form no part of the claimed design.

1 Claim, 3 Drawing Sheets

FIG. 1

FIG. 2

FIG. 3
